and even nonrotating and circumferential efficiency, and the amount of air passing out of the discharge duct of the fan is proportional to the square of the velocity and the square of the discharge pressure.

UNITED STATES PATENT OFFICE

2,634,048

Patented April 7, 1953
John E. McDonald, Newton, Mass., assignor to Westinghouse Electric Corporation, East Pittsburgh, Pa., a corporation of Pennsylvania

Application December 29, 1948, Serial No. 67,820

3 Claims. (Cl. 230—129)

1. A fan system comprising

This invention relates to fan systems in which two or more fans are connected in parallel to a common load.

In many systems, it is desirable to connect two or more fans in parallel for providing more capacity than a single fan can provide, for handling a common load. Thus, it may be desired to connect two fans in parallel to a common outlet duct, with each fan to handle one-half the load. However, it is practically impossible to divide the load in exact equality, since the resistance to the two fans will never be exactly the same in a commercial installation. This is of no consequence in the case of fans such as those having 10 backwardly curved blades, which fans have pressure-volume characteristic curves with steep slopes on which the fans operate, since the steepness of the slopes indicates reserve pressures so that any tendency towards unbalance is at once compensated for by a wide range in developed pressures for but a small change in volume.

However, some fans, such as the radial blade and the forwardly curved blade types, have pressure-volume characteristic curves with portions extending substantially parallel the volume ordinates or having dips. Satisfactory and efficient operation of such fans in parallel may require that the fans operate at points on such portions which may result in instability.

If for any reason, such as a momentary change 30 of resistance, one of two such fans operating in parallel near instability, should deliver less than its proportionate share of load, the second fan would deliver more than its proportionate share of load with resulting increased power consumption and possible overloading of the driving motor. Surging between fans may occur and there may even result a back flow through one fan and a very large flow through the other.

This invention enables fans having operating points on pressure-volume characteristic curves which extend substantially parallel the volume ordinates, or on dips in such curves, to be operated in parallel with stability. The outlets of the fans are connected through converging nozzles to a common exhaust duct, the nozzles of the fans terminating at the same point. The velocity pressures of the fans are increased and their static pressures are correspondingly reduced, resulting in the fans having pressure-volume characteristic curves with steep slopes through their operating points, thus providing stable operation.

An object of the invention is to increase the stability of fans connected in parallel to a common load.

Another object is to eliminate and reduce pressure-volume characteristic curves which result from circumferential and longitudinal air flow in the fan discharge duct, and to provide a fan system which is well suited for use with a fan having a relatively high pressure-volume characteristic curve.

FAN SYSTEM

John E. McDonald, Newton, Mass., assignor to

Westinghouse Electric Corporation, East Pitts-

burgh, Pa., a corporation of Pennsylvania

Application December 29, 1948, Serial No. 67,820

3 Claims. (Cl. 230—129)

1. A fan system comprising

2. Another object of the invention is to operate

fans normally having pressure-volume characteristic curves with working portions extending substantially parallel to the volume ordinates, in parallel, with stability.

Another object of the invention is to operate fans normally having pressure-volume characteristic curves with working portions having dips therein, in parallel, with stability.

The invention will now be described with reference to the drawing of which:

Fig. 1 is a diagrammatic view illustrating a conventional method of connecting two fans in parallel to a common load;

Fig. 2 is a chart showing the pressure-volume characteristic curves of each of two unstable fans operated in parallel as illustrated in Fig. 1;

Fig. 3 is a diagrammatic view illustrating two fans operated in parallel according to this invention;

Fig. 4 is a chart showing the pressure-volume characteristic curves of each of the two fans as connected as illustrated in Fig. 3, and

Fig. 5 is a diagrammatic view illustrating three unstable fans arranged, according to this invention, for stable operation.

Referring first to Fig. 1, the two unstable centrifugal fans 10 have their outlets connected to discharge into a common outlet duct 11. Their inlets 12 may be connected to an upstream load, or the load may be a downstream one connected to the duct 11.

Referring now to Fig. 2, the curve A shows the total pressures of each of the two fans of Fig. 1 for different volumes. The curve B is the static pressure curve for the two fans. The curve C is the load resistance curve for one fan carrying the total load, and the curve D is the load resistance curve for each of the two fans, assuming the load to be shared equally. The operating point of the parallel connected fans is where the curve D crosses the static pressure curve B.

The stability of the fans is determined by the shapes of their static pressure characteristic curves. As illustrated by Fig. 2, the curve B is substantially horizontal on each side of its operating point where the load resistance curve D crosses it. If the resistance offered momentarily to one of the fans is larger than that offered to the other, it tends to drop its load and its operating point tends to shift towards the point of zero volume, while the other fan tends to increase its load, and to shift its operating point towards the point of maximum volume. This action is well known to those skilled in the art, and may result in unstable operation.

However, despite the disadvantage of fans having operating points on horizontally extending pressure-volume characteristic curves, there are some duties where they are preferred. A typical duty is where the fans blow air for combustion into a number of gas furnaces. Operating conditions may require air for one or more furnaces to be shut off, resulting in a decreased load upon the fans. Due to the lack of slope of their static pressure-volume characteristic curves, the drop in load will not cause an increase in pressure, so that the volume of air delivered to each active furnace remains constant. Stable operation of such unstable fans has been accomplished in the past by continuously monitoring their operation, and actuating dampers for adjusting the loads on each fan, or by the use of elaborate, pressure responsive, automatic controls.

According to this invention, the outlet of each fan terminates in a converging nozzle, the outlets of the nozzles of all of the fans terminating at the same point. Figs. 3 and 5 illustrate two embodiments of this invention. Referring first to Fig. 3, the fans 10 are connected through the venturi 14 to the outlet duct 11. The splitter sheet 15 extends from the junction point of the outlets of the two fans into the narrowest portion of the venturi, and provides the similar converging nozzles 16 in the venturi. The air velocities will increase and the static pressures will decrease at the center of the venturi, the drop in static pressure being proportioned to volume. Static pressures measured at the outlets of the nozzles 16 will provide a static pressure-volume characteristic curve B' of Fig. 4 with a steep slope at its operating point where the load resistance curve D crosses it. This results in stable operation of the fans, since the steepness of the slope through the operating point indicates reserve pressure for stable operation.

Fig. 5 illustrates how more than two fans may be connected in parallel, according to this invention, for stable operation. The adjacent walls 18 of the outlet passages 17 of adjacent fans 10, merge together and extend into the narrowest portion of the venturi 14, and form the constricted nozzles 16, the nozzles having the same cross section at their point of merger, which is at the narrowest point of the venturi.

The air after passing through the venturis of Figs. 3 and 5, expands into the outlet ducts 11 in which the total pressure is the same as the sum of the total pressures at the outlets of the individual fans, less the slight losses due to pressure drops in the venturis.

While embodiments of the invention have been described for the purpose of illustration, it should be understood that the invention is not limited to the exact apparatus and arrangement of apparatus illustrated, as modifications thereof may be suggested by those skilled in the art, without departure from the essence of the invention.

What is claimed is:

1. A fan system comprising a plurality of separate, independent fans having separate fan wheels and separate driving shafts for the wheels, each fan having a fixed casing with a gas outlet around its wheel, a plurality of relatively small converging nozzles, one for each fan, each nozzle having an inlet connected to the outlet of one of said fans, a relatively large outlet duct for connecting said fans to a common load, and means forming a single diverging passage connecting the outlets of said nozzles with said duct.
2. A fan system comprising a plurality of separate, independent fans having separate fan wheels and separate driving shafts for the wheels, each fan having a fixed casing with a gas outlet around its wheel, a plurality of relatively small, converging nozzles, one for each fan, each nozzle having an inlet connected to the outlet of one of said fans, said nozzles having outlets arranged in a common plane, a relatively large duct for connecting said fans to a common load, and means forming a single diverging passage connecting said outlets of said nozzles with said duct.
3. A fan system comprising a plurality of separate, independent fans having separate fan wheels and separate driving shafts for the wheels, each fan having a fixed casing with a gas outlet around its wheel, a relatively large duct for connecting said fan to a common load, means forming a Venturi passage connected to said duct, and means forming converging passages connected to the outlets of said fans and terminating in the narrowest portion of said Venturi passage.
